FLOOR LAMP

Cassius B. Lain, Cherryvale, Kans.

Application November 14, 1941, Serial No. 419,195

2 Claims.

(Cl. 240—2)

This invention relates to electric lamps, and its general object is to provide a lamp of the floor type, that includes a stand in the form of an open frame suitably braced throughout its height and shaped to not only be unique and ornamental, but is not easily tipped or toppled over, yet the lamp is light in weight, as it is made essentially of wood, so that it can be readily moved and carried.

An important object is to provide an electric floor lamp including a switch for controlling the illuminating unit, with the switch arranged intermediate the height of the stand a considerable distance below the unit, for disposal in a position so that it is readily accessible and conveniently reached by a person when in a sitting position.

Another object is to provide a floor lamp that includes a platform for supporting articles, and particularly an ash tray within a container fixed on the platform to prevent casual removal, displacement or falling of the tray therefrom.

A further object is to provide a lamp of the character set forth, that is simple in construction, inexpensive to manufacture, and extremely efficient in use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a front view of the lamp which forms the subject matter of the present invention.

Figure 2 is a top plan view of the stand with the illuminating unit removed.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a sectional view taken approximately on line 5—5 of Figure 4, looking in the direction of the arrows.

Referring to the drawing in detail, it will be noted that the base in the form shown is made up of a plurality of strips 1 secured together to radiate an equal distance apart from a common center, and secured to each strip adjacent its

outer end for disposal below the same is a substantially oval shaped foot 2 formed with a shank 3 fixed within an opening in its strip by adhesive material or other means.

Adhesively or otherwise secured within openings disposed in the strips inwardly of the shank receiving openings, are the lower ends of lower uprights 4 and the openings for the uprights are disposed at an angle so that the uprights are arranged in converging relation or inclined toward each other, as best shown in Figure 1. Supported by the uprights is a platform 5 provided with a circular row of openings, with the upper ends of the uprights adhesively or otherwise secured therein.

The platform includes a partially circular main portion and a laterally disposed rounded extension 6 providing a shelf which together with the main portion has pegs 7 secured to and rising therefrom in a circular row for supporting a flat annulus 8 in elevated position for cooperation with the pegs to provide a frame like container for receiving an ash tray 9 that has a match holder 10 and trough like members 11 secured thereto, it being apparent that the members 11 provide rests for cigars or cigarettes. While I have illustrated an ash tray as being mounted in the container, it will be obvious that any kind of receptacle or the like can be mounted therein and is held against casual removal, displacement or falling from the platform in the event the lamp should be tipped.

The platform is provided with a circular row of openings disposed inwardly of the openings for the lower uprights, and adhesively or otherwise secured within the inner openings are the lower ends of upper uprights 12 that are likewise arranged in converging relation or inclined toward each other from the platform, as best shown in Figure 1. Mounted on the upper ends of the uprights 12 is an upper disk member 13 providing the top of the stand and having openings therein, with the uprights adhesively or otherwise secured within the openings.

The upper and lower uprights are provided with bracing means intermediate their ends, and each bracing means includes a disk member 14 having pins 15 secured to and radiating from the periphery thereof, and extending through transverse openings in the uprights, the pins being adhesively or otherwise secured within the openings, as will be apparent. Both the upper and lower uprights are in the form of rods, and the upper uprights are preferably of less diameter than the lower uprights, but the latter are

provided with two bracing means while the lower uprights have one, as clearly shown in Figure 1.

Extending centrally through the base, each of the disk members and the platform is a tubular conduit or pipe 16 having threaded therethrough conductors 17 for the illuminating unit, which in the form shown includes a socket mounted within an upright shade support 18 in the usual manner, and the support 18 is threadedly secured to the upper end of the pipe to bear against a spacing washer or nut 19, or the support can bear directly against the upper disk member 13, but in any event the pipe 16 is held fixed and has a nut 20 threaded on its lower end to bear against the under face of the base, as shown in Figure 1. The shade support is of the usual construction and detachably secured therein is an outwardly flared shade 21 for the lamp bulb 22 which of course is threaded within its socket, not shown.

An important feature of my lamp is the arrangement of the switch 23, as it is disposed a considerable distance below the illuminating unit, so as to be in a position readily accessible and conveniently reached by a person when in a sitting position, as will be apparent upon inspection of Figure 1. The switch is essentially of the usual turn button type in the form shown, with the cap 24 removably secured to the body of the switch casing, and slidably mounted on the pipe 16 to allow ready access to the switch core for replacement or repairs, and the pipe, of course includes upper and lower sections, with the body of the casing threadedly secured to the lower section and the upper section is removably secured within the casing in any suitable manner.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A lamp comprising a stand including a base, feet secured to and depending from the base to underlie the same, an open frame including lower 5 rod like uprights secured to and rising from the base in a circular row and inclined toward each other, a platform for receiving articles and fixed to the upper ends of the uprights for disposal substantially midway the height of the frame, upper rod like uprights secured to and rising from the platform in a circular row and inclined toward each other, an upper disk member fixed to the upper ends of the upper uprights, bracing means for the uprights and including disk members concentrically arranged with respect thereto, pins fixed to the disk members and radiating from the peripheries thereof, said pins being fixed to the uprights for disposing the bracing means in bridging relation thereto, and an illuminating unit supported at the upper end of the frame above said upper disk member.

2. A lamp comprising a stand including a base, substantially oval shaped feet secured to and depending from the base to underlie the same, an open frame including lower rod like uprights secured to and rising from the base in a circular row and inclined toward each other, a platform formed on the upper ends of the uprights for disposal substantially midway the height of the frame, said platform including a partially circular main portion and a round extension directed laterally from the main portion, pegs secured to and rising from the main portion and extension, 35 means fixed to the upper ends of the pegs for cooperation therewith to provide a container for articles, upper rod like uprights secured to and rising from the platform in a circular row and inclined toward each other, a disk member fixed to the upper ends of the upper uprights, bracing means for the uprights and bridging the same, and an illuminating unit supported at the upper end of the frame above the disk member.

CASSIOUS B. LAIN.
